UNITED STATES PATENT OFFICE.

ABRAHAM MASLER, OF NEW YORK, N. Y.

COMBINED MACHINE-COVER AND CHAIR.

1,156,367.

Specification of Letters Patent.

Patented Oct. 12, 1915.

Application filed December 20, 1912. Serial No. 737,877.

To all whom it may concern:

Be it known that I, ABRAHAM MASLER, a citizen of the United States, and a resident of the borough of Manhattan, city of New York, in the county of New York and State of New York, have invented certain new and useful Improvements in Combined Machine-Covers and Chairs, of which the following is a specification.

- 10 The invention relates to convertible devices adapted to be used to cover a sewing or other machine, and when removed therefrom to be used as a chair for the operator. Its objects are, among others, to provide a 15 device of this character of simple, strong and durable construction and effective operation in which the parts are so constructed and arranged that those particularly designed for one purpose will not interfere in 20 any way with the use of the device for the other purpose, the entire device being compact, convenient and easy to manipulate; to provide for the accommodation of articles used in connection with the machine, 25 or other articles; and to further provide means whereby the cover may be locked in its proper position and the locking parts so disposed that they will not become lost or will not interfere with the use or operation 30 of the other parts. To these ends the invention consists in the construction, combination and arrangement of parts herein-after described and claimed and illustrated in the accompanying drawing.
- 35 In the said drawings, Figure 1 is a perspective view of the device with the parts adjusted and arranged to form a chair, looking from the back of the chair and showing the folding braces. Fig. 2 is a perspective from 40 the same point of view as Fig. 1, but with the back of the chair folded. Fig. 3 is a perspective view of the device looking from the front and showing the door of the box open. Fig. 4 is a perspective view of the 45 device with the parts adjusted and arranged to form a box or cover for a sewing machine. Fig. 5 is a longitudinal vertical section of the device with the parts in the position indicated in Fig. 4.
- 50 The device will first be described as a sewing machine cover. When adjusted to form such cover it consists essentially of the large

box-section A having two sides, an end and a cover A', a smaller box-section B, having also two sides, an end and a cover B'. The 55 sides of the section B telescope within the sides of the section A and are connected therewith by means of the pivots C, while the cover B' is in plane with the cover A' and acts as a stop to prevent pivotal movement of the section B when its inner edge comes in contact with the adjacent edge of the said cover A'.

Hinged to the right-hand end of the cover A' (looking from the front) is the chair-back D. This back is also connected to the cover by means of the collapsible bracket consisting of the arms E and E' and the hinge-bar E² connecting them. The opposite ends of the arms E are hinged to the 65 back of the seat-back near its middle and the ends of the arms E' are hingedly connected to the top or cover A', so that the back of the chair may be moved through an arc of 180° to its two normal positions, namely, its 70 position when forming the back of the chair and its position when lying horizontally on the top of the machine cover. Hooks F are also hingedly secured to the cover A', and extend outwardly to engage the bar E² when 75 the chair-back is in its upright position, and the said bar consequently opposite the hinge connections of said hooks in horizontal plane, for the purpose of securing the chair-back in position. When the said back is to 80 be folded over on the cover A' it is necessary only to disengage the hooks F and oscillate it. This will carry with the back the 85 collapsible frame and the hooks.

The smaller box-section B' has a lid G 90 hinged to its left-hand edge (looking from the front), the purpose of which will hereafter appear, and this lid or cover rests against the end of the said section when the device is in use as a cover. The left-hand 95 edges of the chair-box section A are provided with a rubber strip A² which rests upon the floor when the device is adjusted to form a chair and tends to prevent slipping or abrasion of the floor.

When it is desired to convert the device from a cover into a chair the section B is rotated on its pivot through an arc of 180° so that it is entirely housed within the chair-

section A, the lid G—which is of substantially the width of the section A—remaining outside and covering the gap between the end of the section A and the chair bottom end of the end of the section A. A latch H having its pivoted hook secured to the bottom of the section A near its end and its catch on the edge of the lid G is provided for the purpose of holding the said lid in a closed position, and the adjacent edges of the lid and top B' are beveled so that the said lid may be raised to a vertical position and will rest against the beveled edge of the said top B'. The section B is then caused to stand on the edge which is provided with the rubber strip and the chair-back raised and secured in position in the manner hereinbefore described. The device is then adapted to be used as a chair.

It will be seen that the lid G forms a door to a compartment beneath the seat of the chair, and in this compartment various articles may be stored. Sockets J are provided to receive the ends of a spool of tape, or other rotary device, which may be mounted between these sockets if desired.

The locking device consists essentially of the tongue K mounted to slide vertically in the front side of the box-section A and provided with a vertical slot at its lower end adapted to receive a pad-lock or other securing device beneath the table on which the machine is mounted. It also has a loop K' extending through and working in a slot A³ in the front side of the said cover-section, which affords a purchase for the fingers for the purpose of sliding the tongue and also affords a convenient place to hang the lock when it is not in use. The horizontally projecting tongue L on the lower edge of the rear side of the section A is also provided and is adapted to be slipped under the strap M on the table so that the cover cannot be moved when locked.

45 What I claim is:

1. In a device of the character described the combination of an open-bottomed cover made in two sections, each section having four sides and inclosing an uninterrupted space extending from the closed end of one section to the closed end of the other section, a hinged connection between the two sections permitting one section to be turned to a position within the other.

50 2. A combined cover for machines and other articles and chair, comprising a plurality of movably connected sections forming in one position a cover with an opening in one side, and in another position a chair with an elevated compartment within the same and a door closing said compartment, the height of the chair being less than the length of the cover, and the lower extremity of the chair, which in the cover position is disposed vertically, being pro-

vided with yielding material for the purpose of preventing slipping, and serving the purpose of a packing between the edges of the sections while in the cover position.

3. In a device of the character described, the combination of a box or cover having five closed sides and one open side and composed of a plurality of sections movably connected, one of said sections adapted to be moved to a position to partly close the open side of the other section, means for securing the parts so moved in that position, and a back support movably mounted on one section of said cover and within the dimensions thereof, and adapted to be moved to a position in which it projects beyond the same to form a support, and means for securing the same in its extended position, the said movement of the said section causing a shortening of the length of the box so that when it is placed on end it will, with said back support form a chair of suitable proportions.

4. In a device of the character described, the combination of an open-bottomed cover made in two sections, each section having four sides and inclosing an uninterrupted space extending from the closed end of one section to the closed end of the other section, a hinged connection between the two sections permitting one section to be turned to a position within the other, the closed end of the said inside section constructed and arranged to form a shelf or partition within the other.

5. In a device of the character described the combination of an open-bottomed cover made in two sections, each section having four sides and inclosing an uninterrupted space extending from the closed end of one section to the closed end of the other section, a hinged connection between the two sections permitting one section to be turned to a position within the other, and a piece of yielding material on one edge of one of the sections adapted to rest upon the floor when the sections are in the last-named position and to form a packing between the opposite edges of the two sections when they are in another position.

6. In a device of the character described, the combination of a plurality of parts movably connected and forming the top and four sides of a substantially rectangular open-bottomed cover for a sewing machine or other article with a continuous uninterrupted space from end to end and side to side in which the machine may be placed, a back secured to said box or cover and adapted to be folded thereon or moved to a position in which it projects beyond one end thereof, the connection between the cover sections being such that one section may be turned so as to telescope within the other and thereby reduces the length of the

cover and provide it with an interior shelf, and a piece of elastic material on the lower portion of the other section forming a packing between the two sections in the cover 5 position and a non-slip base when the device is in the chair position.

Witness my hand this 17th day of De-

cember 1912, at the city of New York, in the county and State of New York.

ABRAHAM MASLER.
